(57) **CLAIM**

What is claimed is the ornamental design for a knife handle, as shown and described.

DESCRIPTION

FIG. 1 is a perspective view of a knife handle according to the new design;

FIG. 2 is a front view of the knife handle shown in FIG. 1, the rear view being identical thereto;

FIG. 3 is a top view of the knife handle shown in FIG. 1;

FIG. 4 is a bottom view of the knife handle shown in FIG. 1;

FIG. 5 is a left side elevation view of the knife handle shown in FIG. 1; and,

FIG. 6 is a right side elevation view of the knife handle shown in FIG. 1.

Features shown in broken lines form no part of the claimed design.

1 Claim, 2 Drawing Sheets
